The ornamental design for AUDIO CONFERENCING SYSTEM WITH A MIDDLE-MOUNTED VIDEO DISPLAY PANEL, as shown and described.

DESCRIPTION

FIG. 1 is a front, top and right side perspective view of a first embodiment of an audio conferencing system with a middle-mounted video display panel;

FIG. 2 is a front elevation view thereof;

FIG. 3 is a top plan view thereof;

FIG. 4 is a right side elevation view thereof;

FIG. 5 is a front, top and right side perspective view of a second embodiment of an audio conferencing system with a middle-mounted video display panel;

FIG. 6 is a front elevation view thereof;

FIG. 7 is a top plan view thereof; and

FIG. 8 is a right side elevation view thereof.

The evenly-spaced broken lines in FIGS. 1, 2, and 4-8 illustrate portions of the audio conferencing system with a middle-mounted video display panel that form no part of the claimed design. The dash-dot-dash broken lines in FIGS. 5-8 illustrate the boundary of the claimed design which forms no part thereof.
